UNITED STATES PATENT OFFICE

2,090,653

COUNTER FOR STORES

Raymond T. von Palmenberg, New York, N. Y.

Application January 22, 1936, Serial No. 60,152

2 Claims. (Cl. 312—140)

This invention relates to an improvement in counters such as are used in stores for the display of goods for sale.

This invention more particularly applies to 5 counters of the type adapted for adjustable division into sections or bins for the display of varieties of small articles, such, for example, as are sold in the 5 and 10 cent stores.

The improvement in accordance with this invention comprises a combination of elements 10 and variously sub-combinations by virtue of which a counter is provided which has great flexibility for various arrangement to adapt it to contain and display a wide diversity of articles and, at the same time, permitting portions or sections to be dressed at a point remote from the point of display and to be utilized in substitution for portions or sections at the point of display without disarrangement of articles displayed in or on adjacent sections, in or on sections substituted for, or in or on sections dressed at a remote point and used for substitution.

Having now indicated in a general way the nature, purpose and advantage of this invention, 25 I will proceed to a detailed description of a preferred embodiment thereof with reference to the accompanying drawing, in which:

Figure 1 is a perspective view, partly in section, of a counter embodying this invention.

Figure 2 is a sectional view showing details of the embodiment of this invention shown in Figure 1.

Figure 3 is a perspective view of an elevation of the construction shown in Figures 1 and 2.

The counter in accordance with this invention 35 comprises in detail a base *a* supported in any suitable manner, not shown, from the floor of a building, as a store. The base *a* may be supported, for example, on legs, not shown. The base is provided with a vertically extending back *y*.

Upon the base *a* rest shams comprising side members *b*, *b'* and a top *c*. The shams extend from the back *y* to the front of the base. The holes *d*, *d* are provided in the top members *c* along their side edges for the reception of a support formed, for example, of metal and comprising a pin member *e* and spaced wing members *f*, *f* adapted to receive the edge portion of a sheet of glass *g*. Supports may be positioned in the holes *d*, *d* at desired points for the support of sheets of glass, *g*, *g*, in positions to divide a sham or a plurality of adjacent shams longitudinally into a plurality of compartments or bins.

The side members *b'* of the shams are provided adjacent their opposite ends with supports *x* formed, for example, of metal and generally U-shaped. The supports *x* are secured to the outer surface of the members *b'* by means of nails or screws, and are adapted for the reception of the lower edge of a sheet of glass *h* whereby the sheet is supported to extend vertically above and longitudinally with respect to the top *c*.

The members *b* of the shams are provided with recesses *i*, *i* in their outer surfaces corresponding in location and size to the supports *x* secured to the outer surfaces of the members *b'*.

Referring now more particularly to Figure 1, it will be noted that when a pair of shams are arranged together to form a counter having the width of two shams, the supports *x* carried by the member *b'* of one of the shams are received in the recesses *i* in the adjacent member *b* of the adjacent sham, thus permitting the two shams to form a continuous surface. The supports *x* on the opposite members *b'* of the shams, respectively, then serve to support sheets of glass *h*, *h*, which serve to define between them a bin, the back of which is defined by the back *y* of the base *a*. The bin defined by the sheets of glass *h* is divided transversely into a plurality of bins defined by sheets of glass *g*, *g* supported by means of supports, the pin members *e*, *e* of which are entered into selected holes *d*, *d* in the tops *c* of the shams.

It will be observed that the bin defined by the sheets of glass *h*, *h* may be divided by the support of a sheet of glass, from supports *x*, between the shams *c*, *c* on separating the shams sufficiently to remove the supports *x* from the recesses *i* two bins so defined would, as desired, be divided longitudinally by the use of sheets of glass of suitable length in place of the sheets of glass *g*, *g* and suitable supports therefor.

As will be observed, bins of various sizes transversely and longitudinally may be formed on base *a* by the arrangement of shams and of longitudinally and transversely extending glass sheets supported, respectively, from supports *x* carried by the members *b'* of the shams, and from supports the pin members *e* of which are inserted in selected holes *d* in the shams.

Further, it will be observed that shams involved in the formation of bins, as described, may be withdrawn or removed from the base *a* without disturbance of articles carried therein, since the sheets of glass *h* carried by supports *x* associated with the shams will be retained in position with

respect to the shams and will prevent the loss or dropping off of articles therefrom. Likewise, shams may be dressed at a remote point and may be used to replace shams on the base *a*, without 5 disturbance of articles thereon.

It will be understood that this invention is capable of wide variation in detail without departure from the scope thereof and that I do not contemplate limitation thereof to the details given 10 above.

What I claim and desire to protect by Letters Patent is:

1. A sham, a plurality of which are adapted to be used in constructing a store counter, comprising 15 a pair of side members, a top and a support adapted to receive a vertically extending member secured to the outer surface of one of said side members, said other side member having a recess formed in its outer face in line with said support 20 on the first named side member, the recess being

of a size to receive the support secured to the side member of an adjacent sham when a plurality of the shams are assembled and so permit the side members of adjacent shams to be placed in close contact with one another. 5

2. A sham, a plurality of which are adapted to be used in constructing a store counter, comprising a pair of side members, a top and a U-shaped clip adapted to receive and support a vertically extending member secured to the outer surface 10 of one of said side members, said other side member having a recess formed in its outer face in line with said clip on the first named side member, the recess being of a size to receive the clip secured to the side member of an adjacent sham 15 when the plurality of the shams are assembled and so permit the side members of adjacent shams to be placed in close contact with one another.

RAYMOND T. VON PALMENBERG. 20
